METAL MOLD

Allen B. Norton and Marius Guyot, Cleveland,
Ohio, assignors to Aluminum Company of
America, Pittsburgh, Pa., a corporation of
Pennsylvania

Application January 3, 1930, Serial No. 418,362

14 Claims. (Cl. 22—136)

This invention relates to the casting of metal articles in permanent molds. More particularly it relates to a method of and an apparatus for casting thin walled, hollow articles having upwardly converging walls.

It has been difficult to cast in permanent molds, hollow articles having upwardly converging thin walls composed of a light weight metal having a high crystallization shrinkage, such as aluminum or its alloys, and to obtain a casting which will completely fill out the mold cavity and which will be free from air pockets. Another difficulty in casting such articles has been in providing a gate which can be readily and rapidly removed from the casting itself and which will not leave unsightly gating marks thereon. In previously used constructions it has been necessary to utilize molten metal which is heated to an extremely high temperature in order to maintain the metal molten while filling the cavity.

It is an object of this invention to provide a mold for and method of casting hollow articles composed of light metals and alloy including aluminum, magnesium and similar light metals and having upwardly converging thin walls without air pockets therein and without unduly heating the molten metal. It is a further object to provide for the casting of an article of the class described whereby the casting is formed free from unsightly gating marks, the eradication of which is costly and annoying.

Other objects will be apparent from the specification and from the accompanying drawings in which latter

Fig. 1 is a top plan view of a mold assembly embodying my invention;

Fig. 2 is a transverse sectional view taken along line 2—2 of Fig. 1;

Fig. 3 is a detail view of the positioning means for one of the sections of the mold.

Figure 4 is a fragmentary top plan view partly in section of the mold base and core.

Referring particularly to the drawings, one embodiment of this invention is shown as a device adapted to the formation of a washing machine agitator which has an upwardly extending substantially cylindrical hollow portion 1 closed at its upper end and outwardly flaring walls 2 at the base thereof which carry fins or flanges 3 in spaced relation on their upper surfaces. Preferably the article is composed of metal having low specific gravity as compared with iron and including aluminum, magnesium, their alloys or other suitable light metals and their alloys.

The mold for casting the article comprises the relatively movable mold sections 4, 5 and 6 which are supported upon the base 7 and are adapted to cooperate with each other and with a sectional core A to form the casting cavity. The portion of the core A which is to aid in forming the portion 1 of the article can be withdrawn from its operative position to facilitate removal of the cast article from the mold. Ejectors B operate to elevate the cast article from the remainder of the core when the mold sections 4, 5 and 6 are withdrawn therefrom.

The mold sections 4, 5 and 6 cooperate in the following manner:

Each mold section is provided with two straight working faces which meet at an angle forming a substantially wedge-shape. While the sectors of the mold are wedge-shape the meeting faces of adjacent sectors are in face to face engagement and flush with one another. Mold sections 4 and 5 are pivotally mounted upon a pin 10 affixed to the base 7. Mold section 5 carries a pivot pin 11 to which mold section 6 is pivoted for movement toward and from section 5. It will be seen that mold sections 4 and 5 can be swung together about their pivot points bringing work faces of the mold sections into contact with each other and that mold section 6 can be swung about its pivot point bringing its work faces into engagement with corresponding faces of mold sections 4 and 5. The mold faces are suitably recessed to form the casting cavities 12 in which the flanges 3 are to be formed. The adjacent mold sections are also recessed to form the common pouring sprue 13a which communicates through three traps 13b with the three gates 13 which open into an annular runner cavity to be later described and to provide branch gates 14 which open into the upper portion of the casting cavity. Similarly the mold sections cooperate to form the riser cavity 15 at the top of the casting cavity. The mold sections 4, 5 and 6 are secured in operative position by means of a link 17 secured to the mold section 4 and a cam lever 18 secured to link 17 and adapted to bear behind a portion of the mold section 6. The upper portions of the mold sections are clamped together by means of clamping arms 19 and are locked in clamped position by means of the link 20 and cam lever 21. Auxiliary clamps 22 can be provided upon intermediate portions of adjoining mold sections. A pin 25 is provided for holding mold section 5 in position with respect to the base 7. While mold section 6 is being swung into or out of its assembled posi-

tion the pin is supported by brackets 26 and mold section 5 and is adapted to pass through an opening in mold section 5 into an opening 27 in the base 7.

- 5 The core comprises the annular section (see Fig. 2) which is supported by and is affixed to the base 7. Core section 30 carries rigidly a section 31. An elongated core section 32 is disposed in an opening in section 30 for longitudinal movement with respect thereto. Rotational movement between the two core sections is prevented by the key 33. Additional sections 34 and 35 are carried by core section 32. The core sections cooperate with the mold sections to form 10 a casting cavity which is upwardly converging and of irregular contour. The core is provided with a runner recess 36 in its top surface which extends peripherally around and communicates with the casting cavity at a plurality of points. 15 It serves as an inlet for molten metal from the gates 13 to the underside of substantially all portions of the periphery of the bottom of the casting cavity.

As appears from Figures 2 and 4, the core sections 31 stop off or prevent communication for 20 their full width between the annular runner 36 and the cavity for the casting proper. Core sections 31 also carry slight ribs on their upper sides to form radial depressions or grooves on the 25 underside of the casting below ribs 3. The runner 36 thus opens into the casting cavity at a plurality of places which, as shown, constitute a major portion of the entire circumferential length of the runner recess or the periphery of 30 the base portion of the casting proper.

The mold sections 4, 5 and 6 are brought into 35 accurate relation near the top by a pilot member 6a. Below this pilot member the abutting inner faces of the mold sections are suitably recessed to receive and hold accurately in position a central upward rod or extension 32a of the core 32. The purpose of this extension 32a is to 40 position the core at the top and prevent any lateral play or displacement of the upper part of the core. This lateral support insures that the 45 small thin hollow upward extension 1 of the casting will be of the desired shape and dimensions.

Means are provided for withdrawing the core section 32 relative to the remainder of the core 50 A. Core section 32 is provided with an extension 37 which is guided in longitudinal movement by a bracket 38 affixed to the base 7. Member 37 is provided with rack teeth which are adapted to 55 be engaged by the pinion 39 which is actuated in rotary movement by the lever 40 so as to effect longitudinal movement of core section 2.

An ejector mechanism B for elevating the cast 60 metal from the core is supported by the bracket 42 and comprises the pins 43 which are connected with the racks 44 and are adapted to be elevated above or lowered below the top of core section 30. Racks 44 mesh with pinions 45 on shafts 45' which latter carry gears 46 which mesh with 65 each other. One of the shafts 45' is provided with a lever 47 which can be rotated and will elevate or lower the ejector pins 43.

In utilizing the device, with the mold sections 70 and core in their assembled position the molten metal such as aluminum or aluminum alloy or the like is poured into sprue 13a and divides and is apportioned by traps 13b into three streams which flow through the gates 13 into the runner 36 and flows therefrom through the communicating 75 cations between core sections 31 upwardly in

the casting cavity, rising therein to form the portions 2 and 3 of the article and then the portion 4. As the metal rises in the casting cavity additional metal flows into the casting cavity through the bypasses 14 to form the upper portion of the 5 cast article 1 and to supply the casting cavity with molten metal to compensate for crystallization shrinkage of the metal during cooling. After solidification of the metal the mold is opened by releasing the clamps 19 and 22. Mold section 4 10 can now be swung about the pivot pin 10 to open position and mold section 6 can be swung about pivot pin 11 to a position clear of the casting. Positioning pin 25 is removed from engagement with the base 7 after which mold sections 5 and 15 6 are together swung about pivot pin 10 to a position laterally of the cast article.

The casting is now elevated from the core by actuating the lever 47 to raise the ejector pins 43 thereby forcing the casting into an elevated 20 position. When the casting has been removed from the mold the gate metal can be readily broken off, after which the runner metal can be sawed off or cut off in a lathe and the riser metal similarly removed. This leaves the casting 25 with clean smooth working surfaces that do not require any grinding and, for many uses, do not require any polishing and hence the cost of production is lessened while an improved article is obtained.

30 While the invention has been described as applied to the formation of a washing machine agitator it is understood that it is applicable to form articles of irregular contour and of widely varying shapes.

35 While a specific embodiment of the invention has been shown and described it will be apparent that modifications can be made therein within the spirit and scope of the invention and such modifications are intended to be covered by the 40 appended claims.

We claim:

1. A mold for making aluminum alloy castings which comprises a mold base, a core associated therewith having an upwardly projecting member, a plurality of pivoted mold sections carried upon the base, a supplementary mold section pivoted to one of the mold sections, and means to limit pivotal movement of the supplementary mold section with respect to another mold section, the mold sections being adapted to cooperate with the core to form a cavity for a thin walled hollow casting.

2. A mold for casting an article having upwardly converging thin walls which comprises a 55 mold base, a core reciprocably carried thereby and projecting thereabove, a slender upward extension constituting a part of said core, a plurality of mutually pivoted mold sections carried by said base and adapted to surround said core and 60 form therewith a casting cavity, a conical positioning member carried by and in prolongation of said upward extension, inner faces on said mold sections forming a conical recess adapted to clamp said member, thereby holding said core 65 extension in position in said casting cavity.

3. A mold comprising in combination, a base, a core carried by said base and having an annular runner recess in its upper surface, separable mold sections carried by the base and arranged 70 to enclose said core to form a casting cavity therebetween, said mold sections being formed with a feeder extending therethrough and opening into said runner recess and arcuate gates opening into said casting cavity from said run- 75

her recess beginning at points spaced about the runner recess on each side of said feeder.

4. A mold comprising in combination, a base, a core carried by said base and having an annular runner recess therein, a plurality of separable mold sections carried by said base and arranged to close about said core to form a casting cavity therebetween and to enclose said recess to form an annular runner, a plurality of feeders extending through said mold sections and opening into said runner, said core and mold sections co-operating to completely enclose said runners at the junctures therewith of said feeders, and gates opening from said runner into said casting cavity beginning at points spaced on each side of each of said feeders.

5. A mold comprising in combination, a base, a core carried by said base and including a substantially circular portion and a relatively thin axially projecting portion, an annular recess disposed in said substantially circular portion, a plurality of spaced blocks arranged about the periphery of said circular portion and projecting a short distance into said recess, a plurality of separable mold sections arranged to close about said core to form a casting cavity therebetween and to enclose said annular recess, said mold sections engaging said projecting blocks to completely enclose said recess and at other points being spaced from said circular portion to form a gate opening from said recess into said casting cavity and feeders extending through said mold sections and opening into said annular recess.

6. In a mold, a base, a plurality of separable mold sections pivoted to said base and arranged to define a casting cavity, said mold sections having a sprue therein and having three spaced feeders communicating with said sprue and each communicating with the casting cavity at substantially its lowest plane.

7. In a mold, a base, a plurality of mold sections including a pair of sector shaped sections conjointly pivoted to each other and to said base, and a third sector shaped section pivoted to one of said pair of sections, said mold sections being arranged to fit together to define a casting cavity, and means for clamping said mold sections together.

8. In a mold, a base, a core carried by said base, a pair of sector shaped mold sections conjointly pivoted to each other and to said base, a third sector shaped mold section pivoted to one of said pair of sections, said three sections being arranged to enclose said core to define a casting cavity, and means for clamping said mold sections together.

9. In a mold, a base, a plurality of mold sections pivoted to each other and to said base and arranged to define a casting cavity, each of said mold sections having a relatively large portion adjacent said base and a relatively small upward extension, means for clamping said mold sections together adjacent the base, and a clamping ring arranged to surround the upward extensions of said mold sections and clamp the same together.

10. A mold for thin walled castings composed of light metal comprising a base, a core, a plurality of mold sections co-operating with each other and the base and core to form a vertical casting cavity having an enlarged base, and means for introducing molten light metal into the casting cavity including a common pouring sprue, a plurality of gates spaced apart and leading from the sprue, an annular runner extending around

the base of the casting cavity and communicating with the said gates, and opening into the lower portion of the casting cavity.

11. A mold for casting an article having upwardly converging thin side walls and an annular flared base wall which comprises a mold base, a core carried by and projecting above the base defining the inner surfaces of the upwardly converging thin side walls and the under surface of the flared base wall of the said article, said core having an annular runner recess formed therein surrounding the portion of said core defining the under surface of said flared base wall, a plurality of separable mold sections carried by said base and arranged to be closed about said core to define the outer surfaces of the casting cavity for said article, the abutting edges of adjacent sections being provided with mating recesses forming feeders opening into said annular runner recess, and said mold sections being formed to abut said core to close the inner circumference of said annular runner recess at the points where said feeders open into the same, and being spaced from said core intermediate said feeders to provide narrow gates opening into the casting cavity.

12. A mold for casting an article having upwardly converging thin side walls, a flared thin base wall and thin upwardly projecting radial flanges which comprises a mold base, a core carried by the mold base and a plurality of separable mold sections carried by said mold base and arranged to be closed about said core to define the casting cavity, said mold sections and core being recessed to provide an annular runner surrounding the lowermost edge of the casting cavity, the abutting faces of said mold sections being recessed to define the casting cavity for said radial flanges and being separately recessed to define gate passages opening into said annular runner, said mold sections being formed to abut said core to close the inner circumference of said annular runner at the abutting faces of said mold sections, and being spaced from said core intermediate said abutting faces to provide narrow gates opening into the casting cavity, whereby the metal entering the casting cavity for said radial flanges must first pass through the casting cavity for said flared base wall.

13. A mold for casting an article having thin upwardly converging walls and an enlarged base comprising a mold base, a core, and a plurality of separable mold sections carried by said mold base and fitting together with their side edges abutting about said core to define the casting cavity and abutting each other above the top of the core and the casting cavity, said mold sections and core being recessed to form an annular runner recess about the lower-most periphery of the casting cavity, and the abutting edges of said mold sections being recessed to form a plurality of gate passages opening into said annular runner recess and converging upwardly and joining together above the top of said casting cavity and core, and said mold sections being recessed to form a single pouring sprue above and communicating with the juncture of said gate passages, whereby molten metal may be supplied from the single pouring sprue at the top of the mold to said annular runner recess at the bottom of the casting cavity simultaneously at a plurality of spaced points.

14. A mold for casting an article having upwardly converging thin side walls rising from an annular flared base wall and terminating at their upper ends in an integral boss having a relatively small diameter and a relatively thick section inter-

grally joined to the thin side walls, comprising a mold base carrying upwardly projecting core means defining the inner and under surfaces of the article, a plurality of co-operating mold sections carried by said mold base and arranged to close about said core means to define the outer and upper surfaces of said article, said mold sections and core means co-operating to form an annular runner recess surrounding and opening into the lowermost periphery of the casting cavity, the meeting faces of said mold sections being recessed to form gates leading downward between each pair of meeting faces to said annular runner recess, the meeting faces of said mold sections being further recessed to form a feeding riser extending upwardly from and opening into the casting cavity for said thick section boss and said meeting faces being further recessed to form by-passes

opening from said gates and extending inwardly and upwardly therefrom and leading into the casting cavity above the portion of the cavity forming said thin side walls, said gates and annular runner being arranged to feed molten metal into the lowermost periphery of the casting cavity so that the metal rises upwardly through the casting cavity and fills the same and said by-passes being arranged to fill the casting cavity for said thick section boss and said riser with metal at a higher temperature than the metal which has risen through the casting cavity, whereby the metal forming said thin upwardly extending walls will solidify before the metal in said thick section boss and the metal in said boss will solidify before the metal in said riser. 15
